AUTOMATIC TELEPHONE CONSOLE

Felix Gilbert, New York, N.Y., assignor to General
Alarm Corporation, New York, N.Y., a corpora-
tion of Delaware

Filed Oct. 24, 1966, Ser. No. 4,403

Term of patent 14 years

(Cl. D26—14)

Fig. 1

Fig. 2

FIG. 1 is a top plan view of a design for an automatic telephone console;

FIG. 2 is a front elevational view of the console illustrated in FIG. 1;

FIG. 3 is a side elevational view of said console;

FIG. 4 is a rear elevational view of said console; and

FIG. 5 is a side elevational view of said console.

The dominant features of my design reside in the portion shown in full lines.

The handset has been omitted from all figures except FIG. 1 for convenience of illustration.

I claim:

The ornamental design for an automatic telephone console, as shown and described.
